(57) **CLAIM**

The ornamental design for a package of brick packs, as shown and described.

DESCRIPTION

FIG. 1 is an isometric view of a package of brick packs, showing my new design;

FIG. 2 is a top plan view thereof;

FIG. 3 is a bottom plan view thereof;

FIG. 4 is a front elevation thereof; the rear elevation being a mirror image thereof; and,

FIG. 5 is a right side elevation thereof; the left side elevation being a mirror image thereof.

The broken lines define the bounds of the claimed design. The broken lines showing of a package is for illustrative purposes only and forms no part of the claimed design.

1 Claim, 2 Drawing Sheets

FIG. 1**FIG. 2**
